UNITED STATES PATENT OFFICE

RICHARD T. HENNESSY, OF INDIANAPOLIS, INDIANA, ASSIGNOR TO AMERICAN SLICING MACHINE COMPANY, OF CHICAGO, ILLINOIS, A CORPORATION OF NEW YORK

KNIFE-SHARPENING DEVICE

Application filed June 16, 1927. Serial No. 199,207.

My invention relates to a knife sharpening device for application to and combination with a rotary slicing machine. One object is the provision of such a knife sharpener which shall be available for sharpening a manually operated slicing knife. Another object is the provision of a housing for such sharpening means. Other objects will appear from time to time in the course of the specification and claims.

I illustrate the invention more or less diagrammatically in the accompanying drawings, wherein—

Figure 1 is a perspective view of the complete device as applied to a slicing machine having a rotary knife;

Figure 2 is a section on the line 2—2 of Figure 1;

Figure 3 is a section on the line 3—3 of Figure 1;

Figure 4 is a section on the line 4—4 of Figure 3;

Figure 5 is a section on the line 5—5 of Figure 4; and

Figure 6 is a section on the line 6—6 of Figure 2.

Like parts are indicated by like symbols throughout the specification and drawings.

A generally indicates a slicing machine structure having a motor A¹ and a rotary knife A² driven thereby. A³ is the knife shaft with the pulley A⁴ about which passes the belt A⁵ to the motor A¹.

B is a cylindrically formed portion of the structure in which is positioned a bearing sleeve B¹ having roller bearings B² at either end thereof rotatably to support the shaft A³.

C indicates an outward extension of the shaft which has mounted thereon a grinding element C¹ cupped as at C². C³ is a second grinding element cupped in opposition to the cupped portion of the first. C⁴ is an inclined sided steel disc positioned between the two grinding members. The assembly is held to-

gether on the shaft C by means of a left hand threaded screw C⁵ which penetrates the end of the shaft and urges the members C¹ C³ and C⁴ together and against the washer C⁶ which abuts against the shoulder C⁷ on the shaft A³.

In order to provide a housing or closure for the knife sharpening device above described I secure to the cylindrical portion B of the frame an outwardly projecting cylindrical housing member D which is secured to the frame by means of the circumferential flange D¹ and the screws D². Its outer end is closed by the slightly convex member D³ and it is cut away or slotted on its upper side, as at D⁴, in order to give access to the sharpener.

As a closure for said cut-away portion I employ the rotary cylindrical shutter E which is also cut away, in opposition to the cut-away portion D⁴, as at E¹. When the shutter is rotated into closing position the aperture D⁴ is closed by the shutter and the aperture E¹ of the shutter is closed by the housing D. When it is desired to have access to the knife the shutter is so moved that the apertures D⁴ and E¹ are in alignment. In order to limit the rotation of the shutter I employ any suitable stop, herein shown as the screw E² which engages the outer edge of the aperture D⁴ and serves the double function of preventing outward axial movement of the shutter and of limiting its rotation. The end walls of the aperture D⁴ are recessed as at E³, in opposition to the screw E², to permit an exact alignment of the edges of the apertures D⁴ and E¹.

In order to prevent any foreign particles from entering the ball bearing B² I provide a felt packing F, held in position by an apertured disc F¹, having a plurality of inclined spring fingers F², adapted to wedge against the cylindrical housing B as shown in Figures 2 and 6.

It will be realized that whereas I have shown and described a practical and opera-

tive device, nevertheless many changes might be made in the size, shape, number and disposition of parts without departing from the spirit of my invention. I therefore wish my description and drawings to be taken as in a broad sense illustrative and diagrammatic rather than as limiting me to my specific disclosure.

The use and operation of my invention are 10 as follows:

It often happens in the use of a slicing machine of the type herein described that the butcher or delicatessen shop keeper wishes to cut some material with a hand knife, butcher 15 knife or the like. It is therefore desirable to provide means for sharpening such knives and it is an economy to operate such sharpening means from the power plant of the slicing machine. Such sharpening can take place 20 while the slicing machine is actually slicing, or if necessary the slicing machine motor may be actuated in order to permit the operator to avail himself of the sharpening device.

In order to employ the sharpening device 25 the shutter E is moved into the open position with its aperture E¹ overlying the aperture D⁴. The operator then inserts the blade of the knife between the members C¹ and C⁴ or C³ and C⁴, the steel disc C⁴ serving as a 30 guide to thrust the edge at the desired angle against the opposed recessed grinding disc.

I claim:

1. In combination with a shaft and a motor for driving it, and a bearing about said shaft, 35 a knife sharpening device mounted upon the end of said shaft, said knife sharpening device including an inclined sided steel disc and a plurality of cupped abrasive elements mounted one at each side of said disc, and a 40 generally cylindrical housing about said sharpening device, said housing being cut away about a portion of its periphery, and a rotary cap, concentric with said housing and rotatable thereabout, said cap including an 45 extension concentric with the wall of said housing and conforming thereto and adapted to close the cut away portion of said housing, said shaft terminating within said housing and being enclosed by said cap.

2. In combination with a shaft and a motor for driving it, and a bearing about said shaft, a knife sharpening device mounted upon the end of said shaft on the opposite side of said bearing from the rotary knife, said 55 knife sharpening device including an inclined sided steel disc and a plurality of cupped abrasive elements mounted one at each side of said disc, the flanges of said cups terminating in faces lying each in a plane generally 60 perpendicular to the axis of rotation of the shaft, said planes each intersecting one inclined side of the disc, and a generally cylindrical housing about said sharpening device, said housing being cut away about a portion 65 of its periphery, and a rotary cap, concentric

with said housing and rotatable thereabout, said cap including an extension concentric with the wall of said housing and conforming thereto and adapted to close the cut away portion of said housing, said shaft terminating within said housing and being enclosed by said cap.

Signed at Indianapolis, county of Marion and State of Indiana, this 8th day of June, 1927.

RICHARD T. HENNESSY.
